(57) **CLAIM**

The ornamental design for a bracket for a tool, as shown and described.

DESCRIPTION

FIG. 1 is perspective view of the new design, with an environment shown in broken lines that forms no part of the claimed design;

FIG. 2 is a front view thereof;

FIG. 3 is a first side view thereof;

FIG. 4 is a second side view thereof; and,

FIG. 5 is a top view thereof.

The broken lines shown in FIGS. 1-5 illustrate portions that form no part of the claimed design.

1 Claim, 5 Drawing Sheets
